United States Patent Office.

GEORGE JOHNSON, OF CINCINNATI, OHIO.

Letters Patent No. 101,367, dated March 29, 1870.

IMPROVEMENT IN HOISTING-MACHINE.

The Schedule referred to in these Letters Patent and making part of the same.

To all whom it may concern:

Be it known that I, GEORGE JOHNSON, of Cincinnati, Hamilton county, State of Ohio, have invented certain new and useful Improvements in Hoisting-Machines; and I do hereby declare the following to be a sufficiently full, clear, and exact description thereof to enable one skilled in the art to which my invention appertains to make and use it, reference being had to the accompanying drawings making part of this invention.

My invention relates to that class of hoisting-machines in which the platform is raised and lowered by a rope or chain attached to a revolving drum, and consists of certain devices which will instantly stop the revolving drum at any moment that the platform, in its downward course, may be accidentally stopped by obstructions or otherwise.

This invention is designed to guard against the occurrence of disasters to this class of machines resulting from the entanglement and breakage of the rope by the revolving drum, when the platform is accidentally stopped in its descent.

My device is arranged to be operated by the hoisting-rope entirely. When the rope is tight and properly supporting the weight of the platform, the revolving drum is permitted to operate in the ordinary way, the device designed to stop the drum being supported out of gear by the tight rope. When the rope is slack, consequent upon the stoppage of the platform accidentally in its descent, the device for stopping the drum is deprived of support and falls into gear, in such a manner as to stop the revolution of the drum, while the driving-shaft still continues to revolve.

In the accompanying drawing illustrative of my invention—

Figure 1 is a side elevation of a hoisting-machine embodying my invention.

Figure 2 exhibits the device for stopping the drum thrown into gear.

A is the driving-shaft connecting with the motive power in the ordinary way.

The shaft A has rigidly secured to it a head, B, which is provided with spring pawls C C', adapted to engage into the interior notches d d' of the drum D, on which the hoisting-rope E is wound. This construction permits of the drum being revolved by the

power in one direction only, the drum being loose upon the shaft A, and rotated in the direction necessary for raising the platform F by means of the spring pawls C.

When the engine or other motive power is reversed in order to lower the platform, and the rope E is properly supporting the weight of the same, the drum follows the revolving shaft, in consequence of the weight of the platform serving to revolve the drum in that direction.

The drum is provided with a flange or rim, G, whose periphery is notched, as shown.

H is a swinging pawl, adapted to engage in the notches g of the drum, when necessary. It is provided with a grooved pulley, I, into which the rope E fits. This pawl is supported out of gear, as shown in fig. 1, by the rope E, when tight. When the rope becomes slack, by the accidental stoppage of the platform in its descent by obstructions or otherwise, the pawl H falls into the notches g and instantly prevents the rotation of the drum. This effectually guards against the entanglement of the rope, which is of such frequent occurrence in rope hoisting-machines and the cause of so many disasters.

The platform F is provided with the customary safety-catches to prevent the fall of the platform in case of the breakage of the rope.

As a modification of the pawl, a friction-rubber resting upon the drum may be used, if preferred, and the outer teeth of the drum be thus dispensed with.

I claim herein as new and of my invention—

1. The revolving drum D, so constructed and connected to the driving-shaft A and rope or chain E that it will be stopped in its revolution by the pawl H I or friction rubber, in consequence of the slackening of the rope or chain E, as and for the purpose set forth.

2. In connection with the rope or chain E and drum D, constructed and operating substantially as described, the pawl H I, operated by the rope or chain in the manner and for the purpose specified.

In testimony of which invention I hereunto set my hand.

GEORGE JOHNSON.
